ARMCHAIR

Giovanni Offredi, Via Muratori 29, Milan, Italy

Filed Mar. 20, 1973, Ser. No. 343,007

Claims priority, application Italy Feb. 21, 1973

Term of patent 14 years

Int. Cl. D6—01

U.S. Cl. D6—31

FIG. 1 is a front perspective view (looking somewhat downwardly) of an armchair embodying my new design;
FIG. 2 is a rear side perspective view thereof;

FIG. 3 is a front side perspective view thereof; and
FIG. 4 is a top view thereof.

I claim:

The ornamental design for an armchair, as shown.
